Harold George Meyer, North Branch, N. J.

Application August 6, 1952, Serial No. 20,921

Term of patent 14 years

(Cl. D17—6)

To all whom it may concern:

Be it known that I, Harold G. Meyer, a citizen of the United States, residing at North Branch, in the county of Somerset in the State of New Jersey, have invented a new, original, and ornamental Design for a Clip, of which the following is a specification, reference being had to the accompanying drawing, forming a part hereof.

Fig. 1 is a perspective view of a clip, showing my design; Fig. 2 is a top plan view; Fig. 3 is a front elevational view; Fig. 4 is a bottom plan view; Fig. 5 is a side elevational view; and Fig. 6 is a sectional view taken on the line 6—6 of Fig. 3

I claim:

The ornamental design for a clip, as shown.
HAROLD GEORGE MEYER.
